(57) **CLAIM**

The ornamental design for a camera for remote coordinate measuring machine, as shown and described.

DESCRIPTION

FIG. 1 is a top, front and right side perspective view of a camera for remote coordinate measuring machine; FIG. 2 is a front elevational view thereof; FIG. 3 is a top plan view thereof; FIG. 4 is a right-side elevational view thereof; FIG. 5 is a left-side elevational view thereof; FIG. 6 is a rear elevational view thereof; FIG. 7 is a bottom plan view thereof; and, FIG. 8 is a top, rear and right side perspective view thereof. The broken lines depict portions of a camera for remote coordinate measuring machine in which the design is embodied and form no part of the claimed design. The Dot-Dash lines denote the boundary of the claim and form no part of the claimed design. Additionally, the separations depicted by the Dot-Dash lines and brackets indicate break lines for indeterminate length. Any portion of the article between the break lines forms no part of the claimed design.
